[57] ABSTRACT

A pack for transporting a plurality of individual meals ready for service comprises a number of interfitting trays which are stacked into a pack which can quickly be fastened together for stable transport.

4 Claims, 3 Drawing Figures

SHEET 3 OF 3

STACKED TRAYS

The subject of this invention is an arrangement which can be used to put up a plurality of separate meals in a unitary pack which is readily carried, conveniently stowable, and readily disassembled into component parts each carrying a separate meal.

To this end it comprises a plurality of stackable, interfitting trays each formed with recessed compartments to receive foodstuffs, cutlery, drinking vessels, or other amenities, and a cover which is placed on and interfits with the topmost tray and has attached to it a handle and quick-release tie means to retain the pack of trays and cover assembled.

Thus, in use, each tray can be loaded with the elements of an individual meal, the loaded trays stacked one on another, the cover applied, the tie means fastened, so that the meals can be transported in a unitary pack and quickly distributed as and where required.

A facility of this nature can find a very wide range of uses. A primary example is that of family or party picnicing, when the individual meals can be readily laid out prior to the departure for the picnic and be immediately available on arrival at the luncheon site, even in instances where the terrain might normally be awkward for the setting out of a meal. Again, other uses which are envisaged are for example in caravans, in hotels, on aircraft, in trains, coaches, boats or other means of transport, at conferences and so on.

In one advantageous form each tray comprises a top surface with a depending skirt around the perimeter thereof, the junction between this perimeter and the skirt being rebated to interfit with the bottom edge of the skirt of the tray next above it, and locating means comprising lugs constituted by interruptions in said rebating for cooperation with corresponding locating recesses in the said bottom edge of the next tray. This provides for a neat compact and stable pack which can be readily handled without disturbing its assembly and contents.

The tie means may take various forms but in one useful arrangement comprise resilient binding cords with claw clips at the two ends thereof for engagement in said locating recesses in the lowest tray of the pack.

As will be appreciated the layout of the individual trays can vary according to anticipated requirements, but in accordance with a further feature of the invention, one or more of these compartments will be provided with an upstanding rim to receive a sealing lid for the compartment concerned. This will not only help to isolate the compartments from one another, and hence keep the odours from passing between compartments, but will also provide a facility for conserving the particular thermal conditions of the contents, for example certain items may be kept warm even during transport, whilst in other cases it may be ice or other cooling means may be included in the compartment to keep the temperature low.

The cover will of course, preferably follow the outline shape of the individual trays and can have interfitting means corresponding to those on the latter. In addition it will be provided with a carrier handle, and this will advantageously be so devised as not to project beyond the flush surfaces of the pack, and interfere with the stackability of the latter. For this reason the cover may be provided with a central recess and have a han-

dle of bar form spanning this recess and flush with the upper surface of the cover.

A specific form of amenity pack according to the invention will now be described with reference to the accompanying drawings in which:

FIG. 1 is a front view showing the pack assembled and tied;

FIG. 2 is an exploded perspective illustration of the upper part of the pack illustrated in FIG. 1, and

FIG. 3 is a vertical cross section through the assembled pack.

Referring to the drawings, the individual trays of the pack have been designated 1, the cover 2, the carrying handle 3 and the binding cords 4.

Referring now to FIGS. 2 and 3 it will be observed that each tray 1 is of hollow form comprising a main rectangular surface 5 with a depending perimetrical skirt 6. It may be made of a synthetic plastics material, for example polypropylene or hard polyethene, by injection moulding or a vacuum forming method.

In the particular instance illustrated it has a main rectangular recess 7 which can accommodate individual dishes, packages, and so on (not shown), depending on the purpose or function for which the pack is being used at any time. In addition it has a smaller circular recess 8 which again can be used for various purposes, for example to hold a liquid container. A third elongated recess 9 in the tray may be used to house other items, for example plastic cutlery. It will be noted that recesses 7 and 8 have upstanding rims 10, 11 and that corresponding detachable covers 12, 13 may be arranged as a snap sealing fit on these rims for the purpose indicated above.

It will further be observed that the top 5 of each tray 1 is provided with a rounded perimetrical rebate, or groove, 14 which is interrupted at the front and rear sides of the tray to form lugs 15. When the pack is assembled the bottom edge of the skirt 6 of a tray will seat on the rebate 14 of the tray next below it, and the lugs 15 on this latter tray will mate with corresponding recesses 16 provided in the skirt 6 of the first-mentioned tray. This will serve to locate the assembled trays against any relative movement.

The cover 2 is of a shape conforming to that of the trays, and the skirt 17 thereof is provided with recesses 18 for engagement with the lugs 15 of the topmost of the assembled trays. The upper surface of this cover 2 is formed with a central recess 19 and themselves spanned by the carrying handle 3. As will be particularly observed from FIGS. 2 and 3, this handle 3 comprises a channel-form moulding with enlarged ends 20 which are received in corresponding recesses 21 in the cover so that the surface of the handle, when assembled, lies flush with the upper surface of cover 2 (see FIG. 3). The enlarged ends 20 of the handle are themselves provided with separable caps 22 which serve to trap and fasten the tie cords 4 of the pack which are received in these ends 20. The handle, and the caps 22 are held fastened and assembled by fastening nut and bolt arrangements designated 23.

The cords are of strong woven elastic and are provided at their ends with quick fastening claws 24 which engage with recesses 25 in the bottom most tray of the pack. This form of tying of the trays enables the number of those used in the pack to be varied to suit a particular occasion.

I claim:

1. An assembly of stacked interfitting trays, each tray comprising a top with a depending skirt around the perimeter thereof, a groove formed at the junction between the top and the skirt and extending about the perimeter of the tray, said groove interfitting with the bottom edge of an identically shaped skirt of the tray next above it in the stack, each tray having at least two locating recesses in the bottom edge of the skirt and at least two raised lugs formed by interruptions in said groove and extending upwardly from the plane of the bottom of the groove, the lugs being shaped to mate with and positioned along the groove to fit snugly into said recesses of an identically shaped skirt of the tray next above it in the stack, and recessed compartments formed into said top,
and further including,
a cover disposed above the uppermost tray, said cover including a said depending skirt with recesses interfitting with the groove and the lugs of the up-

permost tray, respectively,
a handle attached to the cover,
and a quick release tie means about all of the trays
and the cover for holding the assembly together as
a unitary pack.

5 2. An assembly according to claim 1, in which the tie means comprise resilient binding cords with claw clips at the two ends thereof engaging said locating recesses in the lowest tray of the assembly.

10 3. An assembly according to claim 1, in which at least one of the recessed compartments of each tray is provided with an upstanding rim to receive a sealing lid for the compartment concerned.

15 4. An assembly according to claim 1, in which the cover is centrally recessed and has a bar handle spanning this recess and flush with the upper surface of the cover.
